UNITED STATES PATENT OFFICE.

LEMUEL B. PATTERSON, OF DES MOINES, IOWA.

PRINTER'S CHASE.

1,182,418.

Specification of Letters Patent.

Patented May 9, 1916.

Application filed September 8, 1913. Serial No. 788,752.

To all whom it may concern:

Be it known that I, LEMUEL B. PATTERSON, a citizen of the United States, and resident of Des Moines, in the county of Polk and State of Iowa, have invented a certain new and useful Printer's Chase, of which the following is a specification:

The object of my invention is to provide a printer's chase of simple, durable and inexpensive construction, so made that the rectangular interior opening of the chase, in which the type form to be printed from is placed, is arranged on an angle divergent from the rectangular space in which the chase is clamped within the printing press, whereby the straight rules and type lines will stand at angles divergent from lines drawn through the edges from top to bottom so that inking rollers passing over the type form will not be cut into by the rules or type lines, as sometimes happens where the said rules or type lines are arranged parallel with the outside edges of the chase or the rectangular space in which it lies, and whereby ordinary furniture and quoins may be used inside the chase for spacing and locking the form in position.

A further object is to provide a chase of this class that may be made up of straight metal bars welded together or may be cast as a unit and so arranged that they may be readily, quickly and easily fitted to a particular printing press.

My invention consists in certain details, in the construction, combination and arrangement of the various parts of the device, whereby the objects contemplated are attained, as hereinafter more fully set forth, pointed out in my claims and illustrated in the accompanying drawings, in which the figure shows a perspective view of a preferred form of said chase with a form of type therein, spaced and locked by means of ordinary furniture and quoins.

The sides are preferably beveled at 12 in the ordinary manner. The outer surfaces of the sides and ends of the form of chase shown form a rectangle, as shown, and the inner edges of the sides and ends also form a rectangle, as shown, the inner rectangle, however, being arranged on lines divergent from the lines of the outer rectangle.

In the form of my invention illustrated, the chase is made up of straight metal bars which may be welded together or cast as a

unit. The side bars 13 and 14 are arranged parallel with each other and the end bars 15 and 16 are arranged parallel with each other, the four bars forming a rectangle. In order however to accomplish the purpose of my invention and that the interior opening in the chase may form a rectangle divergent in its outline from the outlines of the rectangular space which the chase is designed to occupy on the press bed, the lower end of the bar 16 and the left hand end of the bar 14 are extended beyond the bars 14 and 15 respectively.

A chase so constructed will lie in a rectangular space in the press bed and will touch at the extended ends of the members 16 and 14 and at the point where the chase is clamped in the bed. The outer surface of the end bar 15, at the upper end of the chase, is planed off to rest in a plane parallel to the vertical plane of the end of the rectangular space in which the chase lies. The bars 13 and 14 are beveled at 17 and 18 so that the rollers in passing over the chase cannot possibly engage a sharp edge. The extended ends of the bars 14 and 16 are designed to be engaged by the walls at the bottom and one side of the press bed in which the chase rests.

It will be seen that with whichever form of the chase used, the rectangular interior opening in the chase will be arranged so that when the form is installed in the chase, as shown in the figure, with ordinary printer's furniture and quoins, the rules 20 and the lines of type 21 will lie in lines somewhat divergent from the lines of the path of travel of the inking rollers. The lower projecting end of the member 14 may be ground or filed off and thereby the chase may be fitted accurately and quickly to the press bed. The beds of different presses, even of the same type and make, may vary slightly in the distance between the rails, and a chase of my preferred form will require comparatively little work in filing off the projecting end of the member 14, to fit the chase accurately to the bed. It will readily be seen that this would be difficult and tedious with a solid rectangular outer frame. The lug 22 may be formed on the member 13 for engagement by a clamp for securing the chase in the press. It will be noted that the lug 22 is so formed as to extend to the upper end of the press bed and so that its upper edge is in line with the

upper wall of the press bed so that it may be properly engaged by the ordinary clamp used for locking rectangular chases in the press.

- 5 In practical use, the form may be placed in the interior of my improved chase and locked in position by means of the ordinary printer's furniture and quoins. The chase may then be mounted in the press bed in
10 the ordinary way.

With the ordinary chase, the form is so placed that when the roller travels over the type or rules, which are arranged in lines across the form from top to bottom, each
15 line of type or each rule is inked and engaged by the roller on the line extending circumferentially around the roller. The roller is frequently cut by the rule and sometimes injured by the line of type. It is
20 also frequently true in such cases that the ink is taken up along a certain circumferential line and part of the type in the form is not well inked. It is often true, therefore,
25 that the ink is not evenly distributed from the top to the bottom of the line.

Where my improved form of chase is employed, the roller passes over the type and the rules in such a way that the line or path on the roller which is engaged is spiral and
30 not circumferential. On this account the tendency for the rules or lines of type to cut into the roller is very largely done away with. It is also true when my improved
35 form of chase is employed that the ink will not be taken up on a circumferential line and therefore the ink is very evenly distributed over the type in the form. Such a construction lengthens the life of the inking roller. At the same time by giving a
40 more even distribution of the ink, it enables the pressman to turn out neater and more perfect printing.

Where the form of the chase, made from bars, as shown, is used, the filing of one
45 comparatively small bar enables the press-

man to quickly and accurately fit the chase to the press.

It will be understood that some changes may be made in the details of the construction of my chase and it is my intention to 50 cover by this application any such changes which may be included within the scope of the following claims.

I claim as my invention:

1. A printer's chase comprising parallel 55 side members and parallel end members, one end member having a longitudinal extension, one side member having a longitudinal extension, said extensions being on the same side but at opposite ends of the chase, and 60 being so shaped that the chase may be set diagonally in a rectangular press bed, with said extensions resting flush against the side and end walls of the press bed, and with one end member of the chase engaging the 65 side wall of the press bed near its upper end, and one side member engaging the upper side wall of said bed.

2. A printer's chase comprising parallel 70 side members and parallel end members, one end member having a longitudinal extension, one side member having a longitudinal extension, said extensions being on the same side but at opposite ends of the chase, and being 75 so shaped that the chase may be set diagonally in a rectangular press bed, with said extensions resting flush against the side and end walls of the press bed, and with one end member of the chase engaging the side wall of the press bed near its upper end, and 80 one side member engaging the upper side wall of said bed, and a beveled member on the side frame member farthest from said extension having one edge parallel with the 85 press bed wall.

Des Moines, Iowa, September 5, 1913.
LEMUEL B. PATTERSON.
